SUN SHADE

Alex Mermelstein, 339 S. Detroit St.,
Los Angeles 36, Calif.

Filed Feb. 17, 1964, Ser. No. 78,658

Term of patent 14 years

(Cl. D88—3)

The fragmentary broken line showing of a support pole is for illustrative purposes only.

I claim:

The ornamental design for a sun shade, substantially as shown and described.
